CARDBOARD CONTAINER

Rene Laflamme, Hull, Quebec, Canada

Application February 24, 1938, Serial No. 192,352

4 Claims. (Cl. 229—19)

My invention relates to packages and, while not limited in use to such goods, in a more specific manner, it relates to packages for cigarettes.

It applies to cigarette packages of the stiff-type, that is to say, to the type made of cardboard and comprising two main parts, namely, case or sleeve and insert or sliding part.

In the conventional package, the insert or sliding part consists of a one-piece sheet of cardboard folded over lengthwise with the length of the cigarettes. The meeting point of the cardboard being towards one end of the cigarettes when this part is withdrawn partly from the sleeve, the short end provides a flap which may be lifted to allow the removal of the contents. However, since the meeting point, as aforesaid, and therefore the flap, is at a certain end of the package, the insert must be withdrawn in one direction only necessitating much attention. The package must be upright and properly turned about to permit the right end of the insert to be withdrawn, a process utterly impossible in the dark.

The main object of my invention is, therefore, to provide a cigarette package which may be opened at either end and which affords equal ease for removal of its contents.

Other objects and advantages will become apparent by perusal of the following description of the preferred embodiment of the invention shown in the accompanying drawings, in which,

Figure 1 is a perspective view of a cigarette package in accordance with my invention in open aspect;

Figure 2 shows the insert or sliding part thereof;

Figure 3 is a plan view of the sliding part blank;

Figure 4 is a plan view of a suggestive tin-foil blank;

Figure 5 is a further plan view of the sliding part blank; and

Figure 6 is a side view of the insert or sliding part.

Similar reference numerals denote identical parts in all the views.

In the drawings 5 indicates the sleeve or outer section of a conventional cigarette package of that type including an inner section of container-like form slidably arranged in said sleeve.

The latter is open at each end and the inner section is closed at its inner end, open at its outer end, formed with a closure flap for its outer end and with the flap releasably held in closure relation with respect to the inner section when the

latter is not extended the desired extent from the open outer end of the outer section to permit of the releasing of the flap to allow access to the contents of the inner section. The sectional package, in accordance with this invention includes an outer section 5 of sleeve-like form corresponding to the form of sleeve referred to, but the inner section generally indicated at 5^a is of a construction different from the said outer section referred to in that one may have access to the contents thereof when such section is selectively extended from the open ends of the section 5.

The insert or inner section 5^a is to be formed from the foldable blanks 5^b, 5^c shown by Figures 15 and 5 respectively.

The blank 5^b consists of a one-piece foldable web having a pair of rectangular portions 6, 6^a providing front and rear walls respectively for closing parts of the front and back of the insert and disposed in offset relation; a foldable oblong portion 11 arranged between opposed sides of the portions 6, 6^a providing one side wall of the insert; a pair of foldable oblong portions 12, 12^a at the other sides of the portions 6, 6^a respectively correlating when folded and secured together to form the other side wall of the insert; a pair of foldable rectangular portions 13, 13^a extended from and of greater width than the portions 6, 6^a respectively and providing the end walls of the insert; and foldable substantially rectangular portions 8, 9 extended respectively from and corresponding in width to the portions 13, 13^a and forming closure flaps for the open parts of the front and back of the insert and for seating 35 against the side walls.

The portions 11, 12, 12^a are disposed at right angles to the portions 8, 9, 13, 13^a. The length of the portions 6, 6^a is less than the length of the portions 11, 12, 12^a. The width of the portions 6, 6^a is materially greater than the width of the portions 11, 12, 12^a. The portion 11 is formed of a pair of parts 11^a, 11^b of like length and width disposed in offset relation (Figure 6). The portion 12 is formed of two parts of equal length 12^b, 12^c, but part 12^c is of greater width than part 12^b. The part 12^c is inwardly offset with respect to part 12^b. The portion 12^a is formed of two parts 12^d, 12^e of equal length, but the part 12^e is of greater width than part 12^d. The part 12^e is inwardly offset with respect to part 12^d. The part 11^a aligns with part 12^c. The part 11^b aligns with the part 12^c. The portion 6 has one end flush with corresponding end edges of the portions 11, 12. The portion 6^a has one of its ends 55

flush with corresponding end edges of the portions 11, 12^a. The portions 13, 13^a are of greater width and are of materially less length than the portions 6, 6^a respectively. The portions 8, 9 correspond in width to the portions 13, 13^a respectively and are substantially of the same length as the portions 6, 6^a respectively. The portions 6, 6^a in length correspond substantially to half of the length of the portions 11, 12, 12^a. The blank is scored between the portion 6 and the parts 11^b and 12^c, between the portion 6^a and the parts 11^a and 12^a, between the portions 6, 6^a and the portions 13, 13^a and between the portions 13, 13^a and the portions 8, 9. The blank when folded to provide the insert and before the latter is inserted in the sleeve 5 will appear as shown by Figure 2.

The correlated side wall forming portions 12 may be secured together by cementitious material; as shown in Figure 5, the correlated side wall forming portions 12^f, 12^g of the blank 5^c are formed with oppositely disposed notches 16 of like form for connecting said portions 12^f, 12^g together. Otherwise than that as stated with respect to the blank 5^c it will correspond in form to the blank 5^a.

The inner section 5^a is illustrated as having removably stored therein cigarettes indicated at 10.

30 In order to satisfy Government regulations, it may be necessary in some cases to make certain that one end of the insert may not be pulled out or opened without the removal of the excise stamp and, to that effect, I may provide a sealing strip 17, as shown in Figure 6, joining the flap 9 to the rear portion of the insert. This strip may be easily removed by the user, after the excise stamp has been removed and the insert has been pushed out for use.

40 It is suggested also that, in the use of a cigarette package made in accordance with this invention, the reading matter may be arranged on the opposite faces of the sleeve to read in opposite directions, so that it will help to indicate the 45 position of the opening flap at each end.

45 As it is customary to first wrap the contents of the package in tinfoil, paper or other material, a suggestive wrapper blank is shown in Figure 4. This blank consists of a rectangular piece 50 of material sufficiently large to completely wrap the contents with sufficient material added along the edges, as shown at 14, to permit overlapping. Cuts 15 may be made to permit easy opening thereof. It is to be clear, however, that any style 55 wrapper may be used in combination with the insert. It is to be understood, further, that changes may be made in the insert to suit various requirements or the course of manufacture without departing from the spirit of the invention 60 as covered by my claims. It is similarly permissible to employ the herein novel insert, or variations therefrom within the above-mentioned scope with cases or sleeves which may differ in shape or style from that shown and described in 65 the specification.

What I claim is:

70 1. A blank for forming a slidable inner container-like section, formed with an open front and back of a two part package having an outer sleeve-like section for encompassing and in which the inner section is slidably mounted, said blank comprising a one-piece web having a foldable inner and a pair of foldable outer oblong portions disposed in parallel spaced relation, said inner 75 portion when folded constituting one side wall of

the inner section, said outer portions when folded correlating to constitute the other side wall of the inner section, a pair of rectangular portions disposed in offset relation with respect to each other, arranged between said inner and outer portions, forming parts of the front and back of said inner section, of less length than the said other portions and each having an end edge aligning with corresponding end edges of said inner oblong portion and one of said oblong outer portions a pair of oppositely disposed foldable rectangular portions of less length and of greater width than and extended outwardly from non-aligned ends of the said other rectangular portions and providing shiftable end walls for said inner section and each for seating against corresponding ends of said side walls, oppositely disposed foldable rectangular portions extended outwardly from the outer ends of the rectangular portions of less length and constituting closure flaps for the open part of the said front and back, and said web being formed with scores to provide for folding the said portions other than the portions forming parts of said front and back.

2. A blank for forming a slidable inner container-like section, formed with an open front and back of a two part package having an outer sleeve-like section for encompassing and in which the inner section is slidably mounted, said blank comprising a one-piece web having a foldable inner and a pair of foldable outer oblong portions disposed in parallel spaced relation, said inner portion when folded constituting one side wall of the inner section, said outer portions when folded correlating to constitute the other side wall of the inner section, a pair of rectangular portions disposed in offset relation with respect to each other, arranged between said inner and outer portions, forming parts of the front and back of said inner section, of less length than the said other portions and each having an end edge aligning with corresponding end edges of said inner oblong portion and one of said oblong outer portions, a pair of oppositely disposed foldable rectangular portions of less length and of greater width than and extended outwardly from non-aligned ends of the said other rectangular portions and providing shiftable end walls for said inner section and each for seating against corresponding ends of said side walls, oppositely disposed foldable rectangular portions extended outwardly from the outer ends of the rectangular portions of less length and constituting closure flaps for the open part of the said front and back, said web being formed with scores to provide for folding the said portions other than the portions forming parts of said front and back, said side walls forming portions being of greater length and of less width than the said front and back forming portions, and said flap forming portions being of greater length and corresponding in width to the said end wall forming portions.

3. A blank for forming a slidable inner container-like section, formed with an open front and back of a two part package having an outer sleeve-like section for encompassing and in which the inner section is slidably mounted, said blank comprising a one-piece web having a foldable inner and a pair of foldable outer oblong portions disposed in parallel spaced relation, said inner portion when folded constituting one side wall of the inner section, said outer portions when folded correlating to constitute the other side wall of the inner section, a pair of rectangular portions disposed in offset relation with

- respect to each other, arranged between said inner and outer portions, forming parts of the front and back of said inner section, of less length than the said other portions and each having an 5 end edge aligning with corresponding end edges of said inner oblong portion and one of said oblong outer portions, a pair of oppositely disposed foldable rectangular portions of less length and of greater width than and extended outwardly 10 from non-aligned ends of the said other rectangular portions and providing shiftable end walls for said inner section and each for seating against corresponding ends of said side walls, oppositely disposed foldable rectangular portions 15 extended outwardly from the outer ends of the rectangular portions of less length and constituting closure flaps for the open part of the said front and back, said web being formed with scores to provide for folding the said portions other than 20 the portions forming parts of said front and back, said inner oblong portion formed of a pair of parts of equal length and like width disposed in offset relation, each of said outer oblong portions formed of a pair of parts of equal length 25 and with one of such parts of greater width than the other, the said rectangular portion forming a part of said front merging into one of the parts of said inner oblong portion and the widest part of one of said outer oblong portions, and the said 30 rectangular portion forming a part of said back merging into the other part of said inner oblong portion and the wide part of the other outer oblong portion.
4. A blank for forming a slidable inner container-like section, formed with an open front and back of a two part package having an outer sleeve-like section for encompassing and in which the inner section is slidably mounted, said blank 35
- comprising a one-piece web having a foldable inner and a pair of foldable outer oblong portions disposed in parallel spaced relation, said inner portion when folded constituting one side wall of the inner section, said outer portions when 5 folded correlating to constitute the other side wall of the inner section, a pair of rectangular portions disposed in offset relation with respect to each other, arranged between said inner and outer portions, forming parts of the front and 10 back of said inner section, of less length than the said other portions and each having an end edge aligning with corresponding end edges of said inner oblong portion and one of said oblong outer portions, a pair of oppositely disposed foldable 15 rectangular portions of less length and of greater width than and extended outwardly from non-aligned ends of the said other rectangular portions and providing shiftable end walls for said inner section and each for seating against corresponding ends of said side walls, oppositely disposed foldable rectangular portions extended outwardly from the outer ends of the rectangular portions of less length and constituting closure 20 flaps for the open part of the said front and back, said web being formed with scores to provide for folding the said portions other than the portions forming parts of said front and back, said rectangular portions forming parts of the front and back of the inner section corresponding in length 25 to half of the length of the said oblong portions, and said flap forming portions substantially corresponding in length and of a greater width than the said rectangular portions forming parts of said front and back for seating against exposed 30 end edges of the side wall forming portions.

RENE LAFLAMME.
